UNITED STATES PATENT OFFICE.

HENRY F. CLARK, OF POUGHKEEPSIE, N. Y., ASSIGNOR TO THE PALMER TORPEDO RAILWAY SIGNAL COMPANY, OF PLAINFIELD, N. J.

ELECTRIC ALARM FOR TORPEDO RAILWAY-SIGNALS.

SPECIFICATION forming part of Letters Patent No. 341,553, dated May 11, 1886.

Application filed December 18, 1885. Serial No. 185,891. (No model.)

To all whom it may concern:

Be it known that I, HENRY F. CLARK, of Poughkeepsie, in the county of Dutchess and State of New York, have invented an Improvement in Electric Alarms for Torpedo Railway-Signals, of which the following is a specification.

Torpedo railway-signals have been made in which a torpedo is placed in position for being fired by a passing train in cases of danger, and there are many places where signals are given to passing trains by means of torpedoes, and such torpedoes become exhausted and the magazine empty, and accidents may occur 15 from carelessness in not replenishing the magazines.

My present invention is made for giving a signal at a depot, switch-house, or station whenever the magazine of the torpedo railway-signal is exhausted, in order that the same 20 may be refilled and danger from the absence of a torpedo avoided. With this object in view I provide a follower within the magazine and an electric circuit with electrodes within 25 or adjacent to the magazine, so that the follower causes a metallic contact with the electrodes and closes the circuit as soon as the last torpedo is conveyed away from the magazine.

The alarm is to be of any desired character 30 placed at or within the switch-house, depot, or other place when the alarm will be most noticeable, so that the attention of the proper person is called to the necessity of replenishing the magazine.

35 In the drawings, Figure 1 shows a torpedo-signal in section with my electric alarm applied thereto, there being also a diagram of the electric circuit containing the alarm device. Fig. 2 is a section; Fig. 3, a sectional 40 plan, in larger size, of the magazine and electrodes; and Fig. 4 is a section, and Fig. 5 is an inverted plan, of the circuit-closing follower.

The torpedo signaling apparatus may be of any desired character. In some of these torpedo signaling devices the torpedoes are supplied by gravity to the slide or other device that takes the torpedo from the magazine to the exploding-anvil. In others of these torpedo-signals the torpedoes are raised by a spring.

45 My improvement is available with any construction of torpedo signaling apparatus. I

have shown the same in connection with the torpedo-signal represented in Letters Patent No. 330,562, granted to me November 17, 1885.

The torpedoes *i* are within a magazine or tube, *t*, and the electric conductors A and B are passed into the magazine or tube near the place where the last torpedo is taken out of or removed from the magazine, and the follower B' acts as a circuit-closer between the 55 terminals or electrodes by coming in contact with such electrodes when the supply of torpedoes is exhausted.

It is preferable to groove the magazine vertically, as shown at E, upon opposite sides of 60 such magazine, and to pass the electrodes up into such grooves, the conductors being insulated from the metallic portions of the magazine, as shown in the drawings, so that the naked electrodes will be exposed, and the ears 70 upon the follower, which pass into the vertical grooves, will come in contact with or rest upon these electrodes when the follower reaches the same in consequence of the supply of torpedoes being exhausted.

I prefer to tip the ends of the conductors 75 with platina to form the electrodes, and to use a copper strip passing across the follower from one ear to the other to form the circuit-closer, and the portions of this strip which 80 come in contact with the electrodes may be plated with platina, in order to prevent the metallic surfaces becoming oxidized.

The electric alarm F is of any desired character, preferably a repeating-bell that rings 85 as the circuit remains closed, and I remark that where a number of torpedo-signals are made use of they should be numbered, and a separate alarm or annunciator correspondingly numbered should be made use of at the 90 station or switch-house, so that it may be readily known which of the magazines is empty.

I claim as my invention—

1. The combination, with the torpedo-magazine, of an electric circuit containing an alarm 95 apparatus, and with terminals or electrodes within or adjacent to the torpedo-magazine, and a circuit-closing follower to come in contact with the electrodes and close the circuit to give an alarm when the supply of torpedoes has become exhausted or reduced, substantially as set forth.

2. A torpedo - magazine having vertical grooves in the inside thereof and insulated electric conductors having their exposed terminals or electrodes within such grooves, in combination with a follower having ears that project into the grooves and act as circuit-closing contacts when such ears come into contact with the electrodes, substantially as set forth.

Signed by me this 4th day of December, A. D. 1885.

H. F. CLARK.
